UNITED STATES PATENT OFFICE.

WILLIAM HUTTON AND WILLIAM JORGENSEN, OF OMAHA, NEBRASKA.

STORM SEWER-INLET.

1,311,819.

Specification of Letters Patent.

Patented July 29, 1919.

Application filed May 7, 1917. Serial No. 167,126.

To all whom it may concern:

Be it known that we, WILLIAM HUTTON and WILLIAM JORGENSEN, citizens of the United States, and residents of Omaha, in the county of Douglas and State of Nebraska, have invented certain new and useful Improvements in Storm Sewer-Inlets, of which the following is a specification.

Our invention relates to sewer inlets and catch-basins, and it is the object thereof to provide a durable, efficient and relatively inexpensive structure for storm-sewer inlets, combining a curb, catch-basin and trap, the main body of the structure being of reinforced concrete and being formed in suitable molds prior to placing it in the position where it is used.

In the accompanying drawings Figure 1 is a front view of a structure embodying our invention, Fig. 2 is a transverse section of the same on the line 2—2 of Fig. 1, and Fig. 3 is an end view thereof.

In the illustrated embodiment of our invention the sewer inlet is designed to be set at the side of a paved street or roadway, in line with the curbing and gutter, and forming in effect a part of the curbing. The structure comprises an upper or mouth-section, and a lower portion or basin, which are formed separately in suitable molds and afterward assembled for use. The lower portion or basin is rectangular in horizontal outline, being open at the top and having a flat vertical front wall 4, rear wall 5, short vertical end-walls 8, a horizontal central bottom-portion 6, and inclined bottom-portions 7 adjoining the ends, all of said parts being in an integral or monolithic body of concrete. Metal reinforcing-rods 9 extend continuously through the bottom-portions 6 and 7, said rods being bent to conform with the longitudinal bottom-contour of the basin. In the front and rear walls 4 and 5 there are horizontal reinforcing rods 10 and 11, and in the end-walls 8 there are horizontal rods 12, all of which extend longitudinally of the respective walls and are embedded therein intermediate the inner and outer surfaces thereof. Reinforcing cross-rods 13 may be placed in the bottom-portions 7, as indicated by dotted lines in Figs. 1 and 3. Through the central portion of the front wall 4 there is extended horizontally one end of a metal pipe elbow 14 having a belled open end-portion 15 which is turned downwardly inside the basin, fitting between the

inner sides of the front and rear walls, and terminating at a level above the bottom-portion 6, so as to leave an unobstructed space between the inclined bottom-portions 6 and 7 and the trap-opening at the belled end 15.

The upper edge of the described basin-member of the structure lies in a horizontal plane, and the lower edges of the upper or mouth-section fit thereon, said upper section 6 having front, rear and end-walls, 16, 17 and 18, which in the assembled structure form upward extensions of the respective walls 4, 5 and 8 of the basin. Only the lower portion of the rear wall 17 is vertical, and above said lower portion the wall is inclined forwardly to join the rear edge of the top-ledge 19. The front wall 16 terminates below said top-ledge, being approximately one-half the height of the rear wall, so that there is a rectangular opening between the adjacent edges of said front wall and top-ledge. The upper edge 20 of the wall 16 is sloped toward the inner side thereof, the end-portions of the sloping surface being slightly higher than the intermediate portions thereof. The front edge of the top-ledge lies in the same vertical plane as the inner side of the wall 16, so that the upper front portions of the ends 18 are shouldered or offset as shown in Fig. 3. A plurality of metal bars 21 have their ends embedded in the front and rear walls 16 and 17, the bars extending diagonally upward from the rear upper edge of the front wall, and being equally spaced longitudinally of the inlet passage to form a grating or guard therefor. In the front wall 16 there are embedded longitudinal reinforcing-bars 22, similar bars 23 and 24 being disposed in the rear wall 17 and top-ledge 19, while in the ends 18 there are bars 25, as indicated by dotted lines in Figs. 1 and 3.

In erecting or placing the structure in position for use, the same is set with the top-ledge 19 in alinement with the upper portion of the curbing A, as shown in Fig. 1, so that said top-ledge forms a continuation of the curbing, while the sloping surface 20 of the wall 16 is alined with the gutter or portion of the road-surface adjoining the curbing. Prior to the paving or surfacing of the roadway, the sewer-pipe B is connected with the projecting portion of the elbow 14', as shown in Fig. 2, and when the paving C is completed the surface thereof is depressed adjoining the sewer-

inlet to form a bowl-like drainage surface leading to said inlet and merging into the sloping top-surface 20 of the wall 16. In Fig. 1 the dotted lines D indicate approximately the line of juncture between the paving surface and the curbing A.

From the foregoing it will be seen that our invention provides a sewer-inlet combining many desirable features in structures 10 of this kind, some of the more important being as follows: The structure is comparatively inexpensive to construct and install, and has such durability as to be practically permanent. The exposed portion of 15 the structure may correspond perfectly with the curbing of which it is a continuation, and thus present a uniform and slightly appearance. A large and free opening is provided for receiving the drainage water from 20 the gutter and surface of the paving, and the bars 21 form an effective guard for preventing more than superficial entrance of solid matter in masses of such size as to clog 25 the sewer. The elbow 14 forms a trap or water-seal for preventing the return from the sewer of noxious gases. The sloping bottom-portions 7 of the basin are flushed by the drainage water and produce a rapid 30 flow of water toward the mouth of the trap, thus tending to prevent the accumulation of sediment either in the basin or trap. It has been found in practice that with sewer-inlets constructed as herein described no 35 clogging of the sewer occurs necessitating more extensive cleaning operations than is afforded by flushing the inlet with a large hose inserted between the bars 21 and extended through the inlet passage down into the basin near the mouth of the trap. The 40 use of a moderate amount of reinforcing

material so strengthens the two concrete members that they may be made up at a central point and transported to the places where used, without danger of breakage thereof, and erected much more conveniently 45 than the structure could be either molded *in situ* or built up from a plurality of smaller members.

Now, having described our invention, what we claim and desire to secure by Letters 50 Patent is:

1. A monolithic combined curb, catch basin and trap provided at its upper portion at the front with a horizontal inlet opening and having its front wall forwardly offset 55 at the lower edge of the inlet opening and its rear wall inclined upwardly and forwardly opposite the said opening and upwardly, and rearwardly inclined bars having their ends embedded in the offset front 60 wall and the inclined rear wall to form a grating.

2. A combined curb, catch basin and trap consisting of a monolithic body having its lower portion tapered from the ends and its 65 upper portion provided with an inclined rear wall forming a taper at right angles to the taper of the lower portion, said upper portion being provided at the front with an inlet opening, and an elbow trap member 70 passing through the front wall of the body at the lower portion thereof and having an arm depending in the lower tapered portion of the body and inclined rods embedded in the inclined portion of the rear wall and 75 in the upper portion of the front wall to form a grating.

WM. HUTTON.
WM. JORGENSEN.
